US0D1042387S

(12) **United States Design Patent** (10) Patent No.: **US D1,042,387 S**
(45) Date of Patent: ** *Sep. 17, 2024

(54) **MOBILE ELECTRONIC DEVICE**

(71) Applicant: **Samsung Electronics Co., Ltd.**, Suwon-si (KR)

(72) Inventors: **Junghyun Choi**, Suwon-si (KR); **Bosoon Kang**, Suwon-si (KR); **Byoungjin Kim**, Suwon-si (KR); **Taeoh Kim**, Suwon-si (KR); **Junyong Song**, Suwon-si (KR); **Woohyeok Jeong**, Suwon-si (KR)

(73) Assignee: **SAMSUNG ELECTRONICS CO., LTD.**, Suwon-si (KR)

(*) Notice: This patent is subject to a terminal disclaimer.

(**) Term: **15 Years**

(21) Appl. No.: **29/860,906**

(22) Filed: **Nov. 23, 2022**

(30) **Foreign Application Priority Data**

May 26, 2022 (KR) 30-2022-0020974

(51) LOC (14) Cl. **14-03**

(52) U.S. Cl.

USPC ..... **D14/138 AB**

(57) **CLAIM**

The ornamental design for a mobile electronic device, as shown and described.

DESCRIPTION

FIG. 1 is a top front perspective view of a mobile electronic device showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a bottom rear perspective view thereof.

The dashed broken lines in the figures depict portions of the mobile electronic device that form no part of the claimed design.

1 Claim, 8 Drawing Sheets
